UNITED STATES PATENT OFFICE

HEYMAN ROSENBERG, OF NEW YORK, N. Y.

HEAT TREATING APPARATUS FOR METAL WORK

Application filed April 29, 1930. Serial No. 448,349.

This invention relates to improvements in apparatus for hardening metal work, and more particularly for case-hardening series or groups of relatively small parts, such as 5 screws, nails, nuts, buckles, small tools, and the like.

Among the objects in view is the improvement of apparatus disclosed in my co-pending applications for patents as follows: Serial No. 372,457, filed June 20, 1929 now Patent No. 1,786,508, dated December 30, 1930; Serial No. 380,350, filed July 23, 1929 now Patent No. 1,806,350, dated May 19, 1931; Serial No. 394,830, filed September 24, 1929 now Patent No. 1,874,122, dated August 30, 1932; Serial No. 394,831, filed September 24, 1929, now Patent No. 1,834,872, dated December 1, 1931, and Serial No. 394,832, filed September 24, 1929.

In greater detail, an object of the present invention is the forced elimination of exhaust products by apparatus so arranged as to obviate danger of excess heating of the moving parts, and other objects are the automatic opening and closing of the discharge door; the effective stopping of the quench tray in the discharging position; the easy and effective disposal of the thermo-couple during a work-discharging operation, and the connecting of parts to facilitate assemblage and dismantling.

With these and further objects in view as will in part hereinafter become apparent and 35 in part be stated, the invention comprises certain novel constructions, combinations, and arrangements of parts as subsequently specified and claimed.

In the accompanying drawings,—

Figure 1 is a view in side elevation of a 40 heat treating apparatus for work embodying the features of the present invention, parts being broken away and seen in section.

Figure 2 is a top plan view thereof.

Figure 3 is a vertical section taken approximately on the planes indicated by line 3—3 of Figure 1, and looking in the direction indicated by the arrow.

Figure 4 is a horizontal section taken ap-

proximately on the plane indicated by line 4—4 of Figure 1 and looking upward.

Figure 5 is a sectional plan showing the automatic door opener and tray stop.

Figure 6 is a detailed, fragmentary section taken approximately on the plane indicated by line 6—6 of Figure 1.

Referring to the drawings by numerals, 55 91 is the furnace housing adapted for use of any appropriate fuel, a gas supply being indicated at 92, preferably controlled in air dilution in the customary manner by the air mixer 93. Furnace 91 has the cover plate 94 having the usual central aperture and supporting a superimposed hearth-like structure consisting of annular plates 95 and 96 rabbeted to interlock and present a substantially smooth upper surface inclined and converging to the aperture of plate 94. The inner margin of annular plate 96 is also preferably rabbeted to accommodate the supporting flange at the upper end of the pot 97 for the cyanide or other salts, so that the upper surface of said flange is substantially continuous of the upper surface of the rings 95 and 96. Thus, any drip of molten salts 60 will drain back into the pot 97. The plate 94 is provided at one edge with pendent portions perforated to provide eyes 98, 98, in which the pintle-like shaft 99 is journaled. 65 The shaft 99 is keyed or otherwise fixed to a lever arm or plate 100, which carries the reticulated work-containing basket 101. The basket may be fixed to the plate 100 in any of various ways, but is preferably arranged 70 to have a bead at its upper end resting in an annular rabbet 102 in the outer end portion of the plate 100 surrounding the opening in the plate, and appropriate clamps 75 103 grip and retain the basket in said rabbet 80 so that the basket will move as the plate 100 is swung incident to rocking movements of shaft 99. At the rear end of the shaft 99 a counterbalance weight 104 is preferably ad- 85 justably fixed to counterbalance the weight 95 of the lever plate 100, and the forward end of the shaft 99 carries a worm gear 105 meshing with a worm 106 carried by a stub shaft 107, and having a beveled gear 108 meshing 90 with an appropriate beveled gear 109 car- 100

ried by a shaft 110 to which is fixed the operating wheel 111. Thus, when the wheel 111 is rotated, the lever plate 110 will be 5 swung and the worm gear will serve to sustain the parts in any given position without requiring the operator to retain his grip on any part of the operating wheel 111. Draining back of molten salts from basket 101 may thus be accomplished with facility, and any 10 other operations will be made convenient which require the lever plate 108 to be sustained in other positions than the lowered position of Figure 1. A housing 112 preferably encloses the operating gears for pintle 15 shaft 99, and parts of said housing provide journal bearings as required. Exhaust products from the burner of furnace 91 escape through an exhaust pipe 113, which is provided with an upwardly discharging portion 20 and a by-pass portion 114. An appropriate gate valve 115 serves to close either the upwardly discharging portion or the by-pass 25 114 as required. A basket 116 is arranged in the line of discharge from the upwardly discharging portion of discharge pipe 113, so that work may be located in the basket and preheated by the exhaust from furnace 91. A chute 117 upstands from basket 116, and the chute and basket are fixed to a shaft 30 118 journaled in the frame 119 in position to be swung to a location with the normally upper end of chute 117 disposed immediately above the basket 101 so as to deliver work to the basket. As previously disclosed, 35 118 perimposed on the furnace 91 is preferably a housing 120, which, of course, is provided with an opening closed by the chute 117 when the chute is in the upright position and enabling the chute to swing to and from its dis- 40 charging position. A door 121 is preferably provided for the side of the housing 120 to enable access thereto as and when required, and a transparent plate 122 may be provided in the door to facilitate visual in- 45 spection of interior conditions without opening the door. The housing 120 is provided with a vertical slot alongside the door 121, which slot is closed by a relatively long slender door 123, and the parts are apertured 50 at 124 and 125 at the lower and upper ends of the door 123. A thermocouple 126 has its lower end portion normally extending into the pot 97 to an appropriate aperture in the lever plate 100, the upper portion of 55 the thermocouple extending through the lower aperture 124. Obviously, the thermocouple is a part of any well known and accepted pyrometer, not illustrated. When the lever plate 100 is to be moved it is necessary, 60 of course, to withdraw the thermocouple, and, for this purpose, the door 123 is opened and the thermocouple lifted until its upper portion lies in the aperture 125, and the door 123 is then closed. The thermocouple thus 65 will rest on the upper end of door 123 and

sustain its parts out of the line of movement of the lever plate 100 and parts connected thereto.

At one side of and preferably substantially below the upper surface of the furnace 91 is arranged the quenching vat 127, which vat is provided with a superimposed housing 128 having the door 129 similar in form and function to door 121. Each of the housings 120 and 128 is preferably provided at its back portion with a sliding gate 130 having an operating handle 131 by which the respective gate is adapted to be slid upward to afford access to the interior of the housing for facilitating repair or other operation within the respective housing. Between the housings is arranged the closure or vestibule 132 preferably made up of separable parts detachably connected together, as by bolts having winged nuts 133, the respective parts of the vestibule portion 132 connected by the said bolts being respectively fixed to housings 120 and 128, so that said housings and parts with which they are connected are separably anchored together by the bolts and winged nuts 133.

Arranged to rest normally within the quenching vat 127 is a work-receiving tray 134 having its rear portion keyed or otherwise appropriately fixed to the pintle-like shaft 135 having a counterbalance 136, adjustably fixed to the rear end of the shaft to counterbalance the weight of the tray 134 and parts carried thereby. Gearing similar to gearing 105, 106, 107, and 108 are arranged in the housing 137 to connect the operating shaft 138 with the shaft 135. An operating wheel 139 is carried by the shaft 138 to facilitate oscillation of shaft 135 to swing the basket 134 from its position in the vat 127 to its discharging position. The basket 134 is, of course, reticulated and provided with baffle 140 for segregating articles of work entering the vat and for preventing back splashing toward the furnace. A supply pipe 141 discharges into vat 127 to deliver the fluid of the quench, which may be water, oil, or other appropriate liquid. A suitable drain 142 is provided for the vat.

The housings 120 and 128 are completely closed, and, in order to enable a discharging action of tray 134, a door 143 is provided and hinged at an upper portion of the housing 128 to close the side of the housing through which the tray moves. A link 144 connects a part of the frame of tray 134 pivotally with the door 143, and preferably a pair of links 144 is employed, one at each side of the tray 134. Each link is pivoted at its lower end, at 145, to a side bar of the tray 134, and again pivoted at its upper end, at 146, to an appropriate bracket detachably fixed to door 143 by a bolt engaged by a winged nut 147. A cross bar 148 is fixed to the tray 134, and has its end portions extend-

ing beyond the side of the tray sufficiently to be positioned for engaging the edges of the respective links 144 as the tray reaches its preferred discharging position.

5 The housings 120 and 128 are closed at their upper ends by appropriate hoods 149 and 150, respectively, each converging to a discharge flue 151 and 152, respectively. Each of said flues is preferably provided with an appropriate slide damper 153 for controlling the discharge through the flues. The flues 151 and 152 lead to and discharge into a mixing housing 154, which mixing housing is in direct communication with the 15 intake side 155 of a forced draft fan or blower 156, which receives the mixed products from flues 151 and 152, and discharges the same through a flue 157. The fan or blower may be driven in any appropriate manner, 20 but preferably by a motor 158 mounted on a bracket 159, which bracket also provides the support for the blower 156. Bracket 159 is sustained by a standard 160 fixed to and up-standing from the main cover plate 94 of 25 furnace 91, but, of course, may be otherwise arranged, or any other appropriate support may be provided as desired for the blower and its cooperating parts.

The vestibule portion 132 is proportioned 30 to snugly accommodate movements of the lever plate 100, and an extension is provided in the form of a tunnel-like hood 161 extending to a position overhanging the vat 124, which hood 161 further assists in preventing back splashing into the furnace housing and aids in shutting off communication between the housings while the plate 100 is within the hood.

It is obvious, of course, that any appropriate receiving means may be provided onto or into which the discharge from tray 134 may occur, one acceptable construction consisting of a hopper 162 sustained on an appropriate framework 163 and preferably 45 discharging into a bucket-like container or other receptacle 164 located beneath the discharge mouth of hopper 162.

The operation is substantially the same as that previously described in my said co-pending applications except for those features distinctive from the previous constructions, and to render clearer the distinctions, the operation may be briefly stated as follows:

55 A charge of preheated work is introduced into basket 101 in any appropriate manner, preferably by the chute 117, when the latter is being used, but the work may be introduced by opening the door 121 and discharging 60 the work from a hand operated container. The pyrometer will then be watched to see when the work reaches the requisite temperature, and, when that has been reached, the door 133 will be opened, thermocouple 136 will be lifted, and the door

133 closed with the thermocouple in the opening 125. Then the operator will rotate the wheel 111 sufficiently for lifting basket 101 out of the molten salts in pot 97. The operator stops the upward movement as soon as the basket 101 is clear, and allows drainage, so that molten salts will not be carried over into the quenching bath so far as avoid- 50 able. After the drainage has been completed, which only requires a moment, the operator continues to move the wheel 111 until the lever plate 100 reaches the discharging position, as indicated in dotted lines. The tray 134 is preferably provided with a stop bar, as shown, to prevent undesirable or exces- 55 sive movement of the lever 101 and its carried parts after reaching the discharging position. As soon as all of the work has been discharged from the basket 101, the operator reverses the movement and returns the basket to its position for receiving a new 60 charge of work. As soon as the basket has been lowered into the vat or pot 97, and the work has been supplied to the basket, the door 123 is again opened and the thermocouple 65 126 lowered until its thermally-responsive resistance is located appropriately in the molten salts to indicate the temperature of the work. Obviously, if the work is being delivered by hand through the door 121, the 70 charge of work may well be introduced into the basket 101 before it is actually lowered into the molten salts, and splashing of the salts will thus be largely obviated. However, when splashing occurs, draining back into 75 vat 97 will be facilitated by the shape of the parts and thus but a minimum amount of the salts will be lost. However, though the 80 draftsman for clearance of disclosure has shown the joints between the rings or annular plates 95 and 96 and between plate 96 and the flange of the vat 97 as open, it is, of course, to be understood that the space or crack in each instance will be filled with an 85 appropriate cement so as to present a continuous, smooth surface. The work, as it 90 discharges from the basket, descends and strikes the baffle 140, and is separated and segregated by the vanes of the baffle, so that 95 each article of work is freed from the immediate influence of close contact with other articles of work, and each article is, therefore, 100 separately quenched under conditions substantially identical with those of all the 105 other articles of work, and mass chilling of 110 work is avoided. Thus, there is no danger of parts of the work within a body or mass retaining heat longer than other parts, and, therefore, not receiving the same degree of 115 quenching action. As the work is quenched, 120 it settles to the bottom of tray 134, and as soon as lever 100 and its connected parts are 125 out of the way, the operator rotates the wheel 139 for swinging the tray 134 to the discharging position. As the tray begins to 130

ascend in its swinging movement, the links 144 cause the door 143 to swing outward in advance of the tray, and this movement continues until the bar 148 strikes the links 144. 5 In this position, the discharge occurs and is practically instantaneous and simultaneous with the striking of links 144 by bar 148. Meanwhile, the baffle 140 will have swung to its open position to allow free discharge. 10 Of course, it is understood that the work during the course of the upward swing of the tray 134 will have traveled along the surface of the tray toward the pivot, and will drop out of the tray nearest the pivot. As 15 soon as the work has been discharged from the tray, the operator reverses the movement of the wheel 139 and the links 144 cause the door 143 to move positively back to its closed position without clashing with or striking 20 the tray.

During all of the operation, the blower 156 will be in action, and the cooler vapors rising in the housing 128 will mix in the mixing housing 154 with the hotter products 25 rising in housing 120, and will thereby reduce the temperature of the latter to a mean temperature below a point of danger or likelihood of injury to the bearings or other moving parts of the blower and its actuator. 30

It should be apparent that the apparatus is of especially compact construction affording maximum work capacity with the occupation of a minimum area, and the advantages incident to this feature are accentuated 35 by the fact that it is not only thoroughly practicable, but is being practiced to arrange plants in tandem or batteries, whereby a furnace and quenching vat are arranged at both sides instead of merely at one side of the receiving hopper 162, or its equivalent, so that a discharge of hardened articles will be received by the hopper first from one side and then from the other, and this tandem arrangement enables even greater compactness 40 and greater productivity in smaller area than occurs with the single plant as illustrated in the drawings, though the compactness and efficiency of the latter are very great. 45

As pointed out in detail in my previous 50 constructions, it is desirable to provide an appropriate handle, such as lever 165, to actuate the rock shaft 118 for swinging the chute to and from its discharging position, and a stop 166 is preferably located to 55 stand from the end of basket 116 to engage frame 119 as the chute 117 reaches the discharging position so as to prevent undesirable or excessive inward movement of the chute.

60 What is claimed is:—

1. In heat treating apparatus for metal work, the combination, with a furnace and salts vat, of a housing for the space above the furnace for confining and directing fumes rising from the furnace and vat, said

housing having an elongated, relatively narrow opening adapted to enable movement of a pyrometer thermocouple to and from a position in the vat, and a door for said opening, the parts being apertured to accommodate said thermocouple in either of its positions. 70

2. In heat treating apparatus for metal work, the combination, with a furnace and a housing for the space above the work, of a pivotally mounted lever located to swing in said housing to and from a position overhanging the furnace, said lever having an aperture in that portion adapted to overhang the furnace, and being provided with a rabbet about the margin of the aperture, a work basket extending through the aperture and having a terminal bead located in said rabbet, and means for securing the bead in the rabbet. 75

80 3. In heat treating apparatus for metal work, the combination, with a furnace and a vat adjacent the furnace, of means for moving work from the furnace to the vat, a housing for the space above the furnace, and a housing for the space above the vat, said housings being arranged to accommodate movement of the work-moving means, and means detachably connecting the housings. 85

4. In heat treating apparatus for metal work, the combination, with a vat, of a reticulated work holder tray in the vat, means for swinging the tray to and from a position in the vat and to and from a discharging position beyond the vat, a housing for the space above the vat having a doorway for accommodating discharging movement of the tray, a door mounted to close said doorway, and means of engagement between the tray and door for shifting the door to an open position as the tray moves toward a discharging position. 95

5. In heat treating apparatus for metal work, the combination, with a furnace and a quenching vat, of housings for the space above the furnace and vat, means intercommunicating the housings, means movable in said housings and intercommunicating means for delivering work from the furnace to the vat, a hood for each of the housings, a flue for each of the hoods, a mixing chamber with which both of said flues communicate, and forced-exhaust means communicating with said mixing chamber. 110

6. In heat treating apparatus for metal work, the combination of a furnace, a vat adjacent thereto and cooperative therewith, forced-exhaust, means for the volatile products from the furnace and vat, and means for mixing said products prior to reaching the forced exhaust means. 120

In testimony whereof I affix my signature,
HEYMAN ROSENBERG.
